Patented Aug. 8, 1854.

UNITED STATES PATENT OFFICE.

JOHN NORTON, OF CORK, IRELAND.

IMPROVEMENT IN BLASTING ROCK, TIMBER, &c.

Specification forming part of Letters Patent No. 11,508, dated August 8, 1851.

To all whom it may concern:

Be it known that I, JOHN NORTON, of Cork, in the county of Cork, Ireland, esquire, captain, late of Her Majesty's Thirty-Fourth Foot, have invented certain Improvements in Blasting, applicable to the blasting of rocks and of timber for the clearing of land and to other purposes; and I do hereby declare that the following specification and accompanying drawings constitute a full and exact description thereof.

The nature of my invention consists, first, in a method of igniting a blasting-charge by what I denominate a "frictional cord," constructed as hereinafter described, and combined with lucifer composition or other inflammable material; and, secondly, in the use or employment of a "safety bridle-guard" to prevent accidental discharge, constructed as hereinafter described.

I use percussion cartridges or tubes charged with fulminating-mercury or other highly-explosive compound, which are introduced into holes bored in the rock or other substance to be blasted or ruptured, in lieu of an ordinary charge of gunpowder, and are ignited by percussion instead of a fuse, as practiced when blasting with gunpowder.

The manner in which I prepare my percussion-cartridge is shown in Figures 1 and 2, 5 and 6, of the drawings hereunto annexed, Fig. 1 being an external elevation, and Fig. 2 a longitudinal section, and Figs. 5 and 6 details.

A is a plug of wood or metal, which forms the base of the cartridge, and to which the thin cylindrical metal casing B is attached. This casing may, however, be formed of paper, linen, or other suitable material, waterproofed by a coating of caoutchouc or gutta-percha.

C is a plug similar to the base A, which

is inserted in its place, the casing must be filled with fulminating-mercury or other highly-explosive compound. The pin and upper plug must then be inserted and the casing fastened round or over the plug. When the cartridge is about to be used, a hole in the rock or other substance to be blasted must be bored out and the cartridge inserted therein. Upon the top of the cartridge a bar of metal or wood is placed, and by striking the end of the bar which projects from the hole bored the cap will be detonated and the discharge of the blasting compounds effected.

The mode in which this improved cartridge is employed in the blasting of timber for clearing land is substantially as follows: A triangle is made of three tall spars placed over the root to be blasted, a hole being bored by an auger an inch and a quarter in diameter into the most gnarled part of the root. A gouge-rimer is good to use after the auger, as it cleans away the rough interior and admits the cartridge freely. About three inches deeper than the center a plug of iron of the same diameter of the auger and an inch and a half long, or a small round stone, is forced into the bottom of the hole, so as to prove a solid foundation. A rammer of iron of nearly the same diameter as the auger, about four inches longer than the depth of the hole, so as to project about four inches, is then inserted, and may or may not rest on the head of the cartridge. A block of wood or other material of about sixty pounds weight, suspended by a strong cord vertically over the projecting head of the rammer, is then allowed to fall on it, when, by the momentum or blow, the explosion takes place, and in no one instance has the rammer been blown out, or, as military engineers term it, "gunning" occurred.
